UNITED STATES PATENT OFFICE.

CHARLES B. HALDEMAN, OF CENTER TOWNSHIP, CLOUD COUNTY, KANSAS.

FEED-TROUGH.

No. 900,277.

Specification of Letters Patent.

Patented Oct. 6, 1908.

Application filed June 8, 1907. Serial No. 378,020.

To all whom it may concern:

Be it known that I, CHARLES B. HALDEMAN, citizen of the United States, residing in Center township, in the county of Cloud and 5 State of Kansas, have invented certain new and useful Improvements in Feed-Troughs, of which the following is a specification.

This invention relates to feed troughs, and my object is to produce a mouse and chicken 10 proof trough of this character which can be employed with any kind of grain or feed.

A further object is to produce a feed trough which hogs can readily open and obtain 15 access to the feed and which will close automatically when the hog withdraws his head.

A still further object is to produce a feed trough of simple, strong, durable and inexpensive construction.

To these ends the invention consists in 20 certain novel and peculiar features of construction and organization as hereinafter described and claimed; and in order that it may be fully understood reference is to be had to the accompanying drawing, in 25 which—

Figure 1, is a view partly in end elevation and partly in vertical section on the dotted line I of Fig. 2, of a feed trough embodying my invention. Fig. 2, is a view partly in 30 top plan and partly in section on the line II—II of Fig. 1. Fig. 3, is a view partly in central vertical longitudinal section and partly in side elevation.

In constructing the feed trough, galvanized or other suitable sheet metal will preferably be employed, though of course I do not restrict myself to the use of any particular material or combinations of materials.

In the said drawings, 1 indicates the base 40 plate and 2 longitudinal angle irons secured in any suitable manner to the base plate at its side margins.

3 indicates a substantially inverted-U-shaped body arranged longitudinally upon 45 and centrally of the base plate and secured to the latter at its lower ends as at 4 or otherwise, this body forming a magazine 5 for the feed and from which the same is adapted to pass automatically through openings or 50 slots 6 in the body portion into the troughs 7 formed by and between the body portion, the base and angle irons 2. The body por-

tion is provided with an opening 8 through which the charge or supply of feed is introduced to the chamber 5, a suitably hinged or 55 other door 9, being employed to control said opening 8, the door having a handle 9^a for convenience in opening or closing it.

10 indicates end walls corresponding in contour to the cross sectional form of the 60 body portion and forming the ends of the magazine chamber, said end walls and body portion being united reliably together by angle irons 11, and to brace the body portion, a band 12 is secured to and around it the side 65 portions of the body having outwardly projecting flanges 13.

14 indicates brace bars which extend up through and are secured rigidly to flanges 13, and down through and are secured 70 rigidly at their lower ends to angle irons 2 so as to constitute a series of inclined braces to stiffen and strengthen the structure as a whole and also form supports for a series of lids 15 which form closures for the troughs 75 7, each series of lids being provided with loops 16 at their upper ends engaging a hinge rod 17 supported in a series of eyebolts 18, depending from flanges 13 and secured to the latter by nuts 19, the lower ends 80 of the lids resting upon the upper edges of angle irons 2 and curving outwardly and upwardly therefrom as at 20, in order to give a hog a convenient projection under which to root for the purpose of opening the 85 lid and giving access to the food in the troughs, it being understood that the openings 6 connecting the magazine and troughs 7 may be made larger or smaller in effect by means of the slide valves 21 fitting against the 90 outer sides of the body portion and provided with parallel slots 22 engaging guide pins 23, projecting outward from the body portion and engaged by clamping or wing nuts 24, the latter being for the purpose of securing 95 the slides at the desired point of adjustment, it being understood that certain grain will fall or feed more readily than other kinds and that because of this fact the slides may be adjusted to accommodate 100 the particular type of feed in or to be placed in the body portion.

Each end of the troughs is closed by an end wall 25 which fits against the endmost

braces 14 and against the contiguous portions of angle irons 11, base 1, and angle irons 2, and is provided at such points respectively with outwardly projecting flanges 5 26, 27 and 28, secured to angle irons 11, base 1 and angle irons 2 respectively, by rivets or in any other suitable manner, the base flanges 27 being cut away at their ends so that said end walls shall fit properly over 10 the outwardly projecting flanges at the lower ends of the body portion and base flanges of the angle irons 2. If desired each lid may be provided with a hook 29 for engagement by any one of the links of a chain 30, attached at its upper end to an eye bolt 31 secured to the body portion. This chain is employed for the purpose of holding the lid partly open so that a pig can see and smell 15 the feed and thereby be induced to root under the lid to obtain access to the feed in the troughs. After the pigs are thus educated 20 the use of the chains may be discontinued.

From the above description it will be apparent that I have produced a feed trough 25 possessing the features of advantage enumerated as desirable and I wish it to be understood that I do not desire to be restricted to the exact details of construction shown and described as obvious modifications will suggest 30 themselves to one skilled in the art.

Having thus described the invention what I claim as new and desire to secure by Letters Patent is:—

1. A feed trough, comprising a base, an inverted-U-shaped magazine secured to the base and provided in its lower edges with 35 openings, angle irons secured to the base parallel with and outward of the sides of the magazine, angle irons secured in the opposite 40 sides of the magazine, inclined brace bars connecting the angle irons secured to the magazine with the angle irons secured to the base at the corresponding sides of the magazine, end walls between the opposite 45 sides of the magazine, the base and the angle irons secured to the latter and forming in conjunction with said magazine, base and angle irons, troughs in communication with the magazine through the openings of the 50 latter, and lids hinged at their upper ends to the angle irons secured to the magazine and resting at their lower ends upon and projecting outwardly beyond the angle irons of the base at the corresponding sides of the 55 magazine; each lid lapping over the adjacent pair of brace bars.

2. A feed trough, comprising a base, an inverted-U-shaped magazine secured to the base and provided in its lower edges with 60 openings, angle irons secured to the base parallel with and outward of the sides of the magazine, angle irons secured to the opposite sides of the magazine, inclined brace

bars connecting the angle irons secured to the magazine with the angle irons secured to 65 the base at the corresponding sides of the magazine, end walls between the opposite sides of the magazine, the base and the angle irons secured to the latter and forming in conjunction with said magazine, base and angle irons, troughs in communication with the magazine through the openings of the latter, lids hinged at their upper ends to the angle irons secured to the magazine and resting at their lower ends upon and projecting outwardly beyond the angle irons of the base at the corresponding sides of the magazine; each lid lapping over the adjacent pair of brace bars, and adjustable valves for controlling the openings connecting the magazine and the troughs. 75

3. A feed trough, comprising a base, parallel angle irons secured to the same at its side margins, a substantially inverted U-shaped body portion fitting upon the base 85 and secured thereto and provided in the lower edges of its opposite sides with openings and provided also with a door-controlled opening in its upper portion, end walls at the ends of said inverted-U-shaped 90 body portion, angle irons securing said body portion and end walls together, a band around the magazine constituted by such body portion and end walls, provided with outwardly projecting flanges, brace bars secured at their upper ends to such flanges and at their lower ends to the angle irons of the base, end walls for the troughs fitting against the outer edges of the endmost brace bars and secured to the base, its angle irons, 95 and the body portion, eye-bolts depending from the flanges of said band, rods extending through said eye-bolts and lids pivoted on said rods and resting upon and projecting outward of the angle irons of the base 100 and overlapping adjacent brace bars.

4. A feed trough, comprising a base, parallel angle irons secured to the same at its side margins, a substantially inverted U-shaped body portion fitting upon the base 110 and secured thereto and provided in the lower edges of its opposite sides with openings and provided also with a door-controlled opening in its upper portion, end walls at the ends of said inverted-U-shaped 115 body portion, angle irons securing said body portion and end walls together, a band around the magazine constituted by such body portion and end walls, provided with outwardly projecting flanges, brace bars secured at their upper ends to such flanges and at their lower ends to the angle irons of the base, end walls for the troughs fitting against the outer edges of the endmost brace bars and secured to the base, its angle irons 120 and the body portion, eye-bolts depending 125

from the flanges of said band, rods extending through said eye-bolts, lids pivoted on said rods and resting upon and projecting outward of the angle irons of the base and
5 overlapping adjacent brace bars, and means for supporting the lids partially opened if desired.

In testimony whereof I affix my signature, in the presence of two witnesses.

CHARLES B. HALDEMAN.
